REMOTE-CONTROL APPARATUS WITH
AUTOMATIC LIMIT PROVISION

Michel N. Yardeny, New York, N. Y.

Application July 27, 1945, Serial No. 607,306

4 Claims. (Cl. 318—31)

1

This invention relates to remote control apparatus of the follow-up type for placing, from a control point, a load at a remote point in any desired position by means of the energization of an electric motor at the remote point.

It is inherent in the design of remote control apparatus of the follow-up type that, while the position of the load can be controlled from a control point and the load can be placed in any desired position, the position of the load at any given moment during the positioning of the load does not bear any definite relation to the position of the control device. As a result, the load may be moved into a position which will cause damage to the load, for instance, the movable plates of a variable capacitor may be forced beyond their limit positions.

One object of the invention is to provide limit means for a follow-up system by which the load is automatically stopped when reaching a limit position independently of a further manipulation of the control device.

Another object is to provide a remote control apparatus with automatic limit positions, as described, with means for braking the motor when deenergized.

For the attainment of these and such other objects as may appear or be pointed out herein, there is shown an embodiment of the invention in the single figure which is a diagrammatic illustration of the remote control system provided with the aforementioned improved features.

The control device at the control point comprises a pair of relatively movable members, one of which is an insulated disc 20 and the other a contact arm 10, both of which are mounted for rotation about a spindle 9. Insulated disc 20 carries a pair of electrical conducting elements in the form of segments 21, 22 adjacent ends of which are separated by a gap 19, 19. Conducting elements 21, 22 are connected to collector rings, respectively, 23, 24, engaged by respective stationary brushes 25 $\times$, 26 $\times$, which are connected by leads 25, 26 to the outer terminals of a pair of relays 27, 28. The inner terminals of relays 27, 28 are connected by short leads 27 $\times$, 28 $\times$ to a lead 29, connected to a wire 8 leading through a switch 5s to one terminal 7 of a source of current.

The contact arm 10 is provided with a distal contact element 10 $\times$, which is slidably engageable with the conducting segments 21, 22 and is connected at its proximal end by a lead 6 to a supply wire 5 connected through a switch 5s to the other terminal 4 of the current source. Contact arm 10 is selectively adjusted to engage one

2

or the other of the contact elements 21, 22 to energize the proper one of the relays 27, 28 to cause motor rotation in the desired direction. For example, if contact arm 10 is adjusted, by manipulating knob 10 ζ , counter-clockwise from the position shown in the figure to engage conducting element 21, a circuit will be completed through relay 27, which circuit may be traced from one supply terminal 4, through lead 6, contact arm 10, engaged segment 21, collector ring 23 and brush 25 $\times$, lead 25, to the outer terminal of relay 27, from whence through short lead 27 $\times$ and common lead 29, to wire 8 leading to the other supply terminal 7.

15 Energization of one or the other of the relays 27, 28 causes energization of the respective ones of the field windings 47, 48 of load motor 40 and respective windings 37, 38 of the pilot motor 30, the function of which is to turn one of the pair 20 of relatively movable members (in the illustration shown, the insulated disc 20) in a direction to cause realignment of gap 19 and contact element 10 $\times$ of the contact arm 10 to cause stopping of load motor rotation. For this purpose, shaft 31 25 of pilot motor 30 is provided with a pinion 31 ζ which meshes with a gear 20 ζ secured to rotate with the insulated disc 20.

The armatures of the relays 27, 28 are effective to energize respective ones of the field windings 30 37, 38 of pilot motor 30, and field windings 47, 48 of load motor 40, depending upon which one of the relays is energized—in the following manner: Each of the relays 27, 28 is provided with a pair of armatures, the armature associated with relay 27 being an inner armature 15 and an outer armature 17; the armatures associated with the other relay 28 include an inner armature 14 and an outer armature 16. The armatures are shown in the figure in their unattracted position when both relays 27, 28 are deenergized. It has been described above that engagement of the contact arm 10 with conducting segment 21 results in energization of relay 27. Energization of relay 27 attracts its both armatures 15, 17 to complete 45 a circuit to field windings 37 and 47, respectively, of the pilot motor 30 and of the load motor 40. The circuit to field winding 37 of the pilot motor 30 may be traced from one supply wire 5, through a lead 1, to a contact 2 associated with the relay 50 28, through the unattracted armature 14 of deenergized relay 28, a short lead 13 connecting the proximal ends of the armatures 14, 15, attracted armature 15 of energized relay 27, a contact 35 of relay 27, lead 36 to the outer terminal 55 of field winding 37, from the common winding

terminal, through a lead 32, to the other supply wire 8. Simultaneously with the energization of field winding 37 of pilot motor 30, field windings 47 of load motor 40 is energized through the completion of a circuit which may be traced from the short lead 13 connecting the proximal ends of armatures 14, 15, which is connected, as already traced, to the supply wire 5, through a short lead 12, lead 11, to a contact 19 associated with relay 27, through attracted armature 17 of energized relay 27, short leads 17^x, 16^x, unattracted armature 16 of deenergized relay 28, a contact 45 of relay 28, lead 46, to the outer terminal of field winding 47 of load motor 40, from the inner common terminal thereof through a lead 8' to the other supply wire 8.

Load motor 40 is provided with a pinion 40_p meshing with a gear 50_g secured to rotate with the load 50. Energization of field winding 47 of load motor 40 causes turning of the load in the desired direction. Energization of field winding 37 of pilot motor 30 causes rotation of the pilot motor in a clockwise direction to cause the insulated disc 20 to be turned in a counterclockwise direction to bring gap 10 into alignment with the contact arm 10 which had been assumed to be turned counter-clockwise to engage conducting segment 21. It will be noted from the figure that when the gap 19 is aligned with contact arm 10, the contact element 10^x bridges the gap so as to engage both conducting segments 21, 22 simultaneously. This causes energization of both relays 27, 28 to cause attraction of their armatures, resulting in breaking of the circuit to both the pilot motor 30 and the load motor 40. Selective adjustment of the contact arm 10 in a clockwise direction to engage the other segment 22 causes energization of the other relay 28, to energize the other field winding 38 of the pilot motor and the other field winding 48 of the load motor 40 by completion of circuits similar to the ones traced in the instance when relay 27 is energized.

The system is further provided with an electromagnetic brake illustratively represented by its coil 39 adapted to positively stop the rotation of the pilot motor 30 automatically when both field windings 37, 38 are deenergized. The coil 39 of the electromagnetic brake is connected in a circuit which may be traced from the common terminal of the field windings 37, 38 through a short lead 39^x, through the electromagnet coil 39 and by a lead 34 to the juncture of the aforementioned short leads 17^x, 16^x connecting armatures 17, 16. The electromagnetic brake is designed to spring press its braking element into operative position to stop motor rotation when its electromagnetic coil is deenergized and to withdraw the braking element when the coil is energized. When either one of the armatures 17, 16 is in attracted position to complete a circuit to one or the other of the windings 47, 48 of the load motor 40 and when one or the other of the field windings 37, 38 of the pilot motor 30 is energized, a circuit will be completed from supply wire 5, as previously traced, to the short lead 17^x, 16^x and through the lead 34 to pass through the electromagnetic coil, continuing through short lead 39^x and lead 32 to the other supply wire 8; hence, when the field windings of the motors are energized for directional rotation of the respective motors, the electromagnetic coil 39 will be energized to withdraw its braking element. When the motors are stopped by bridging of the gap 19, in the manner already described to cause energization of both relays 27, 28, and the open-

ing of the circuits to the field windings of both motors, the circuit through electromagnet 39 will likewise be broken and the spring thus rendered operative to stop the rotation of the pilot motor. A similar automatic electromagnetic brake may be applied to the load motor, if desired.

The load 50, for purposes of illustration shown in the figure in the form of a rotative disc, has a limited extent of angular movement of 180° between contact 51 and contact 52. Contact 51 is connected by lead 53 to the lead 25 which, as already described, connects the outer terminal of relay 27 with the collector ring 23 associated with conducting segment 21; the other limit contact 52 is connected by a lead 54 to the lead 26 which connects the outer terminal of the other relay 28 with the collector ring 24 associated with the other conducting segment 22. The load, represented by disc 50, is connected at its proximal point by lead 5' to the supply wire 5 and is further provided at its periphery with a contact 50^x. When the load disc 50, in turning, for example, in a counter-clockwise direction,—as a result of energization of field winding 47 and the energization of relay 27 (by reason of the circuit already traced), reaches the limit of its range of restricted movement defined by the contact 52, the contact 50^x, secured to rotate with the load disc 50, engages the contact 52 to complete a circuit to energize the other relay 28. This circuit may be traced from supply wire 5, through lead 5', contact 52, lead 54, lead 26, to the outer terminal of relay 28, from the inner terminal thereof, through short lead 28^x and lead 29, to the other supply wire 8.

Relay 27 already being energized to cause the said counter-clockwise rotation of the load, the energization of the other relay 28 will cause both relays to be energized and their armatures 40 to be attracted and thus to disconnect the circuits to both load motor 40 and the pilot motor 30, thus causing the load to be stopped at the limit defined by limit contact 52. Similarly the load will be stopped at the limit defined by limit contact 51 during rotation in a clockwise direction when relay 28 is energized.

The advantage of connecting limit contacts 51, 52 in the manner described to cause the energization of the relay other than the one energized to cause the load rotation in the desired direction and thus to energize both relays, resides in the fact that under no circumstances can there occur a reversal in motor direction. For example, should the contact arm 10 align with the gap 19, at a time just preceding the engagement of the load contact 50^x with one or the other of the limit contacts 51, 52, there would occur a reversal in motor rotation if the alignment were such that upon engagement of 50^x with one or the other of the contacts 51, 52 the respective relay were to be deenergized. The alignment of gap 19 and contact arm 10 causes the energization of both relays 27, 28. If the arrangement were such that the engagement with one or the other of the limit switches 51, 52 resulted in a deenergization of the respective relays, then the other relay would remain energized and cause rotation of the load motor (and also the pilot motor) in the reverse direction. By providing that the limit switches 70 51, 52 cause energization of respective ones of the relays 27, 28, this could never occur even when both relays are energized by the alignment of gap 19 and contact arm 10.

I claim:

75 1. In a remote control device of the follow-up

type for moving a load in either direction to desired positions, in combination, a reversible motor for moving the load, a pair of movable members, one of the members having a pair of electrical conducting elements separated by a gap and the other member having a contact element engageable therewith, a pilot motor operatively connected with one of the said pair of members for moving the same, a pair of relays connected in circuit with respective ones of the said conducting elements and controlling circuits for the load motor and the pilot motor, the other of the said pair of movable members being selectively movable by other means to engage the said contact element with one or the other of the said conducting elements to energize its respective relay for directional rotation of the said load motor and pilot motor, rotation of the pilot motor turning the first said member in a direction to re-align said contact element and gap and engage the said contact element with both conducting elements to energize both relays, thereby stopping motor rotation, a contact secured to rotate with the said load, and limit contacts connected in circuit with respective ones of the said pair of relays, said limit contacts being positioned to be engaged by the rotating contact for energizing the relay other than the one energized by the said engagement of contact element and conducting elements, whereby both relays are energized to stop motor rotation.

2. In a remote control device of the follow-up type for moving a load in either direction to desired positions in combination, a reversible motor for moving the load, a pair of movable members, one of the members having a pair of electrical conducting elements separated by a gap and the other member having a contact element engageable therewith, a drive means operatively connected with one of the said pair of members for moving the said member, a pair of relays connected in circuit with respective ones of the said conducting elements, the other of the said pair of relatively movable members being selectively adjustable by other means to engage the said contact element with one or the other of the said conducting elements to energize its respective relay for directional rotation of the said load motor, the said drive means being arranged to turn the first said member in a direction to re-align said contact element and gap and engage the said contact element with both conducting elements to energize both relays to stop motor rotation, a contact secured to rotate with the said load, and limit contacts connected in circuit with respective ones of the said pair of relays, said limit contacts being positioned to be engaged by the rotating contact for energizing the relay other than the one energized by the said engagement of contact element and conducting elements, whereby both relays are energized to stop motor rotation.

3. In a remote control device of the follow-up type for moving a load in either direction to de-

sired positions, in combination, a reversible motor for moving the load, a pair of movable members, one of the members having a pair of electrical conducting elements separated by a gap and the other member having a contact element engageable therewith, a pilot motor operatively connected with one of the said pair of members, a pair of relays connected in circuit with respective ones of the said conducting elements, the other of the said pair of relatively movable members being manually adjustable to engage the said contact element with one or the other of the said conducting elements to energize its respective relay for directional rotation of the said lead motor and pilot motor, rotation of the pilot motor turning the first said member in a direction to re-align and contact element and gap and engage the said contact element with both conducting elements to energize both relays to stop motor rotation, limit switches connected in circuits with respective ones of the said pair of relays, and means secured to rotate with the said load for actuating the said limit switches to energize the relay other than the one energized by the said engagement of contact element and conducting elements, whereby both relays are energized to stop rotation of both motors.

4. In a device of the follow-up type at a control point for moving a load at a remote point in either direction to desired positions, in combination, a reversible motor for moving the load, relays electrically connected to control the directional rotation of the motor, a device at the control point having a pair of relatively movable members, one of the members being manually adjustable to energize the relays for the desired direction of motor rotation, a pilot motor at the control point electrically connected to be controlled by the said relays for moving the other member into a direction and positioned to control the relays to stop rotation of said load and pilot motors, limit switches electrically connected to the said relays, and contact means secured to rotate with the load for actuating the switches to control the relays for stopping rotation of said load and pilot motors when the load contact has reached one of the said two limit contacts.
